UNITED STATES PATENT OFFICE.

CHARLES R. SWAIN, OF PEEKSKILL, NEW YORK, ASSIGNOR OF ONE-HALF
TO WILLIAM D. SOUTHARD, OF SAME PLACE.

TELEPHONE-SIGNAL.

SPECIFICATION forming part of Letters Patent No. 359,984, dated March 22, 1887.

Application filed March 19, 1884. Serial No. 124,730. (Model.)

To all whom it may concern:

Be it known that I, CHARLES R. SWAIN, a citizen of the United States, residing at Peekskill, in the county of Westchester and State 5 of New York, have invented a new and useful Improvement in Telephone-Signals, of which the following is a specification.

My invention relates to signals and alarms in connection with telephone magneto-call 10 bells; and its object is, first, to give notice to persons who may have been absent from their rooms or places of business of the ringing of the telephone call-bells during such absence; second, by means of an auxiliary bell, to give 15 notice at a distant point of the ringing of the telephone call-bell; and, third, to call any one of several subscribers who may be connected with a single line. I attain these objects by the mechanism illustrated in the accompanying drawings, similar letters referring to similar parts throughout the several views.

Figure 1 is a front elevation of my device in its normal position. Fig. 2 is an elevation showing that the bells have been rung, and 25 also disclosing the details of my device. Fig. 3 is a side view illustrating further details and my manner of ringing an auxiliary bell, and Fig. 4 is another form of my device.

My device consists of the common form of 30 annunciator-drop applied to a magneto-bell case, as in Fig. 1, in which A A' represent the bells as used on the ordinary telephone-case.

B is the bell-hammer.

D is the drop or shutter, hinged at 1 to a 35 frame that may be constructed in two ways, as at C in Figs. 1 and 3, in which the frame C is screwed directly on the face of the bell-case, or as in Fig. 2, in which C is provided with projecting arms a b, by means of which the 40 frame may be suspended from the screws that secure the bell-adjusters, as shown by the dotted lines in Fig. 1. The provision of this method of hanging the drop is to anticipate any objections that might be made to driving 45 screws into the bell-cases.

Pivoted to frame C at 2 is the bell-crank c c', notched at the end of arm c' to inclose the bell-hammer lever. The end of arm c bears a catch, d, as shown in Fig. 3. Spring E is 50 fastened at its lower end to pin 3, and its upper end hooks into the lever at 4 and tends

to keep the lever against pin 5. The projecting edge of arm c, into which the spring is hooked, serves also as a stop for the drop when it is pressed to its normal position. The form 55 I give to d admits of the drop being readily pushed to its place within the notch. To save time and trouble to the operator this lever must always be in position to catch the drop as soon as it is thrown by the touch of a finger to its place; hence the employment of spring E and pin or stop 5; but as the power that vibrates the bell-hammer is a light one spring E requires to be so adjusted as not to counterbalance that power, which is easily 65 done.

The normal position, then, of the bell-hammer B, lever c c', and drop D is shown in Fig. 1. The first stroke of the hammer will be against A', carrying arm c' to the right, lifting 70 arm c, with its catch d, releasing the drop, which falls. If the last electric impulse should leave the hammer against bell A', the force of the spring would restore it to the position shown in Fig. 1. 75

In case a business man cannot always be in his office, yet wishes to respond promptly to telephone-calls, as the coal-dealer, for instance, I propose placing an ordinary electrical call-bell in the coal-yard, or a distant part of business or other premises, and connecting it in circuit with my annunciator and a local battery, as indicated in Fig. 3, in which one end of a line is connected with frame C and the other terminates in a spring, as at e. The 85 dropping of the shutter D closes the circuit. Of course a single line may be used with the terminals grounded, or the circuit may be constituted in other known ways. When frame C is hung as in Fig. 2, spring e would be attached to the frame, with proper insulation. This arrangement is particularly advantageous in cases where prolonged ringing is necessary or desirable—in calling physicians—and by it arrangements can be made with central offices, 90 or with other subscribers, for early calling of mornings, and the ringing would only require a moment of time in turning the magneto-call by the caller. 95

Another form of constructing my annunciator is illustrated in Fig. 4, in which I use a straight lever instead of a bell-crank lever. 100

The action is the same; but owing to the slight movement given to the short end of the lever the catching-points *i i'* require rather too much delicacy for practical use, and I prefer my 5 other plan.

What I claim as my invention, and desire to secure by Letters Patent, is—

1. A telephone-signal consisting of a frame having arms by which it is held in position by 10 the screws that hold the bells in place, in combination with an annunciator-drop hinged to it, and a lever, one end of which engages with the drop and the other end with the bell-hammer, substantially as shown and described.

2. In a combination of an annunciator-drop 15 with the bells of a magneto-call box, the arms *a* and *b* of frame C, by means of which the screws that secure the bell-adjusters are made available for supporting the frame C, substantially as shown and described, and for the purpose set forth.

CHARLES R. SWAIN.
